CLARENCE M. BEARD

BY

Danny Schmedemann
ATTORNEY

UNITED STATES PATENT OFFICE.

CLARENCE M. BEARD, OF BERKELEY, CALIFORNIA.

GARDEN-HOSE SUPPORT.

Application filed July 15, 1922. Serial No. 575,258.

To all whom it may concern:

Be it known that I, CLARENCE M. BEARD, a citizen of the United States, residing at Berkeley, in the county of Alameda and 5 State of California, have invented certain new and useful Improvements in Garden-Hose Supports, of which the following is a specification.

My invention is an improved holder for 10 garden hose.

The object of my invention is to provide a means whereby the holder may be easily adjusted to accommodate it to various sized hose.

Another object of my invention is to provide 15 a holder which is simple in construction and inexpensive to manufacture.

Referring more particularly to the drawing:

Fig. 1 is a side view of my holder.

Fig. 2 is a top plan view of the same with the clamping plate extended.

Referring more particularly to the draw-

ing, the numeral 1 indicates a pointed rod which is adapted to be inserted in the 25 ground. A loop 2 is formed on the upper end of the rod 1 and passes through a flexible clamping strip 3. In one edge of the strip 3 are formed a plurality of L shaped notches 4, which receive the rod and hold 30 the strip firmly around the hose as shown in Fig. 1.

Having described my invention, I claim:

A stake, a flat flexible member pivoted at the upper end of the stake at one end, 35 the other end of said member being readily adjustable relative to said stake in order to support hose of different diameters between said member and the stake, said member being formed with a plurality of notches 40 for receiving the stake therein, the hose when supported thusly being pressed against the stake on one side.

In testimony whereof I affix my signature.

CLARENCE M. BEARD.
